UNITED STATES PATENT OFFICE.

HENRY WEBSTER, OF NEWPORT, KENTUCKY.

CONTINUOUS MUFFLE-KILN.

1,362,158.

Specification of Letters Patent. Patented Dec. 14, 1920.

Application filed February 27, 1920. Serial No. 361,845.

To all whom it may concern:

Be it known that I, HENRY WEBSTER, a subject of the King of Great Britain, and a resident of Newport, in the county of Campbell and State of Kentucky, have invented certain new and useful Improvements in Continuous Muffle-Kilns, of which the following is a full, clear, and exact description, reference being had to the drawings forming a part of this specification.

My invention relates to the construction of muffle kilns for the burning of that grade of goods which must not come in contact with the fire such as terra cotta, enameled ware, pottery and the like.

My object is to provide such a kiln in which the muffles may be constructed in units to be operated in series or separately as desired and in which provision is made for the most perfect economical and uniform heating of the muffle on all sides by drawing the fire and heat over the sides and top and down through the muffle and back and forth over the bottom.

It is also my object to provide a construction in which any one or more of the units in the series may be cut out temporarily for repairs or otherwise and the fire carried completely around the muffle chamber without interference with the firing of the remaining muffle and without heating or affecting in any way the muffle or muffles which are withdrawn from use.

My objects are attained by that novel construction and arrangement of flues and furnaces in the manner to be hereinafter particularly pointed out and claimed, in which the furnaces, except for the ends of the complete structure, are arranged along both sides of the muffle chambers and in which the chambers are divided into separate units by a blank wall, with the flues so arranged as to carry the heat completely around each muffle, with dampers to direct the heat from one muffle chamber to the next in series or to by pass any desired muffle chamber or chambers.

In the drawings,

Figure 1 is a plan view of one unit with the underground flues and floor plan of two succeeding units in horizontal section.

Fig. 2 is a cross section of one unit taken through the down draft flues of the muffle.

Fig. 3 is a central longitudinal section of same showing the connection with adjacent units.

Fig. 4 is a cross section of the main flue and connections taken on a median line between two of the units.

Fig. 5 is a cross section taken through the transverse passage and flues intermediate two of the units looking toward the blank wall separating the units.

The main body of the kiln 1 is constructed of such length as desired with the arched roof 2 and divided into sectional units by blank walls 3 built solidly across the kiln. The sectional units are also arranged in series side by side with the main flue connecting with the chimney flue between the several series. In each chamber 5 formed by the blank walls 3 is constructed on the floor 4 of the chamber a muffle 6 with solid end walls 7, 7, and arched side walls and top to correspond with and a convenient distance from the side walls and arch of the muffle chamber to allow for the passage of the heat and products of combustion all around the ends, sides and top of the muffle, one end wall of the muffle being located a like distance from the blank wall 3.

To support and brace the side walls of the muffle brace walls 9, 9, are provided extending from the side walls of the chamber.

The furnaces 8, 8 for each chamber with grates 10 are arranged along the sides of each chamber, so as to deliver the heat and flames over the side walls of the muffle.

Down through each muffle near the blank wall end of the muffle and opening through the arched top are a series of down draft flues 12, 12. These flues extend vertically down through the muffle and are preferably arranged as shown with two flues at the center and the others near the side walls.

These flues extend down through the floor of the kiln and open into underground ducts 13, 14, which extend lengthwise under the muffle and around the division walls and back under the muffle floor to outlets 39 underneath the blank wall 3 into a transverse passage-way 15 across the end of the muffle chamber. From this passage-way when closed at the ends by dampers as will

be described the products of combustion from the furnaces pass over the wall 16 into the adjoining muffle chamber, the wall 16 for each chamber being built only as high as the arch of the muffle.

The transverse passage-ways 15 are connected at their inner ends with a waste heat flue 18 which runs the entire length of the kiln sections so that any heat that is not needed for the next section may be turned into the waste heat flue for use either for other sections or for use in other parts of the plant for heating purposes.

Ordinarily the connection between the transverse passage-ways 15 and the waste heat flue 18 is controlled by dampers 31. From the waste heat flue openings are also provided controlled by dampers 32 into the passage-way 19 which connects directly with the transverse passage 15 at its upper end and has a lateral connection with the main flue 20 controlled by damper 33.

This main flue 20 also runs the entire length of the kiln and underneath the center of one kiln unit connects with a transverse flue 21 to the chimney 22. The chimney it will be understood can be located at any convenient point, although I have illustrated it in the drawings as outside the kiln 30 and opposite the middle section shown.

Along the outside of the kiln structure underground and also in connection with the transverse passage 15 I provide an additional flue 23 running the entire length of 35 all the sections.

This flue, as stated, connects with each transverse passage 15 and the inlet is controlled by a damper 24 at each connecting point. These dampers are normally closed 40 but in the event that for repairs or otherwise it is desired to cut out any section or sections I open up the flues 13, 13 by knocking out a removable portion 25 at the inner end of the unit next the one to be cut out, 45 which allows the heat and flames to enter the adjoining transverse passage instead of traveling back underneath the muffle and then by opening up the damper 24 this heat is carried into the flue 23 and thence is carried past the section to be cut out.

By proper control of the dampers by knocking out the ordinarily blocked off portions 25, 25, the heat instead of being carried into the next muffle chamber over 55 the wall 16 may be carried directly under the floor of the muffle chamber through the passages 14.

As a further provision for controlling the heat I also provide a lateral passage 35 for 60 the front end of the passages 13, 14, underneath the muffle floor which passage is controlled by damper 36 normally closed but which can be opened to turn the heat into the waste heat flue 18 instead of taking it 65 back underneath the muffle floor.

Each muffle is provided with a door 27 or passage-way on each side for convenient use and the main and transverse underground flues are provided with dampers for closing off any set of passage-ways and man-holes 70 28 are also provided at convenient points for access to the flues.

It will be understood that all of the units are constructed in exactly the same way and that the series of units when arranged in 75 parallel rows are connected with the main flue 20 on each side.

The operation of the kiln will be obvious from the foregoing description. As many units are built as desired and they can all 80 be fired at the same time through the furnaces for each muffle chamber, or the heat from one set of furnaces can be utilized for the succeeding muffles. The muffles are so constructed that the heat can be applied for 85 each muffle on every side and for the bottom and the heat from one set of the furnaces can be utilized for the succeeding sets.

It will be understood that as many unit chambers will be built as desired for the 90 full capacity of the plant and additional chambers added as required. Any number of the units may be utilized at a time and the muffles may be omitted from any of the chambers. Any kind of fuel may be used 95 for firing and the heat generated by the furnaces of one unit will pass through all of the succeeding chambers or not as the operator may desire by proper control of the dampers in opening up or closing the flues. 100

Having thus described my invention, what I claim as new and desire to secure by Letters Patent is:—

1. A kiln of the character described, comprising a series of heating chambers with a 105 solid wall dividing the chambers from each other, furnaces along the sides of the kiln opening into their respective chambers, a muffle in one or more of said chambers, hot air flues opening downwardly through the 110 muffle floor with lengthwise passages underneath the floor traversing the length of the muffle and connection therefor with the main flue, said hot air flues extending through the roof of the muffle and opening 115 into the heating chamber whereby the muffle may be heated in all sides uniformly.

2. A kiln of the character described, comprising a series of heating chambers with a solid wall dividing the chambers from each 120 other, furnaces along the sides of the kiln opening into their respective chambers, a muffle in one or more of said chambers, hot air flues opening downwardly through the muffle floor near one end of the muffle with 125 lengthwise passages underneath the floor traversing the length of the muffles and a baffle wall in each passage to cause the products of combustion to travel back and forth underneath the muffle with openings for 130

said passages into the next adjoining heating chamber whereby a continuous circulation may be maintained.

3. A kiln of the character described, comprising a series of heating chambers with a solid wall dividing the chambers from each other, furnaces along the sides of the kiln opening into their respective chambers, a muffle in one or more of said chambers, 10 hot air flues opening downwardly through the muffle floor near one end of the muffle with lengthwise passages underneath the

floor traversing the length of the muffles and a baffle wall in each passage to cause the products of combustion to travel back and forth underneath the muffle with openings for said passages into the next adjoining heating chambers whereby a continuous circulation may be maintained, with a lateral passage at the termination of the baffle wall 20 and damper for controlling same whereby the heat may be diverted from its passage back underneath the floor of the muffle.

HENRY WEBSTER.
